UNITED STATES PATENT OFFICE.

ALBERT H. DRAKE, OF WEST VALLEY, NEW YORK.

POWER-DEVELOPING DEVICE.

Application filed May 16, 1924. Serial No. 713,820.

To all whom it may concern:

Be it known that I, ALBERT H. DRAKE, a citizen of the United States, residing at West Valley, in the county of Cattaraugus 5 and State of New York, have invented new and useful Improvements in Power-Developing Devices, of which the following is a specification.

This invention relates to power devices, 10 particularly to mechanical movements, and has for its object the provision of a novel device for converting reciprocatory motion into rotary motion, the device being adapted for use in connection with a windmill, rocking chair, rocking horse, engine pitman or in fact any other power device and acting to convert or translate such intermittent reciprocatory movement into a substantially or entirely continuous rotary motion for applying 15 power to washing machines or other domestic appliances or in fact any mechanism or device desired to be driven.

An important object is the provision of a device of this character in which dead center 20 is overcome and in which means is provided for readily throwing the mechanism out of gear when desired.

The invention further contemplates many improved details of construction and arrangement in devices of this general class 25 so as to constitute a general improvement in the art.

With the above and other objects and advantages in view the invention consists in 30 the details of construction to be hereinafter more fully described and claimed and illustrated in the accompanying drawings, in which:—

Figure 1 is a side elevation of the mechanism.

Figure 2 is a longitudinal section therethrough.

Figure 3 is an end view showing the device mounted in a different manner.

Figure 4 is a section at right angles to Figure 2.

Figure 5 is a fragmentary view showing the pawl mechanism in elevation.

Figure 6 is a detail section showing the mounting of the pawls.

Figure 7 is a section illustrating a modification.

Figure 8 is a perspective view of one of the pawls.

Figure 9 is a section on the line 9—9 of Figure 3.

Figures 10 and 11 are detail views of the cams used for rendering the device inactive in the form disclosed in Figure 7.

Figure 12 is a section showing the pawl 60 release used in the form shown in Figures 2 and 4.

Figure 13 is a detail perspective view of the pawl releasing levers.

Figure 14 is a section on the line 14—14 of 65 Figure 5.

Referring more particularly to the drawings the numeral 10 designates a rectangular supporting frame of any desired size and construction, depending upon the intended 70 size of the whole device and the purpose for which it is to be used as well as the power generator providing the drive. This frame may conveniently be of channel or angle iron so as to possess strength and rigidity. 75 At opposite sides of the frame are bearings 11 and at one end are other bearings 12.

Journaled in the bearings 11 is a shaft 13 which does not extend entirely through the bearings and which is therefore prevented 80 from having longitudinal movement. Rotatably mounted on this shaft are large bevel gears 14 which mesh with a pinion 15 on the shaft 16 to be driven, which shaft is journaled in the bearings 12. The shaft 16 might 85 be provided with a gear, pulley or other means by which power may be taken off. Formed upon or secured to the gears 14 are ratchets 17 which have their teeth oppositely arranged.

The operating means comprises an elongated lever 18 which has a hub 19 rotatably engaged upon the shaft 13. This hub is of considerable length so as to extend within recesses 20 in the confronting faces of the gears and ratchets so as to have proper bearing surface and to be prevented from improper movement. Throughout a portion of its length the opposite sides of this lever 18 are toothed or ribbed as indicated 95 at 21 so as to provide secure holding means for brackets 22 which are similarly ribbed or toothed and which are held on to the lever by bolts 23 or the like passing through slots 23a. These brackets are formed with guides 24 for plungers 25 which terminate in pawl heads 26 co-operating with the respective ratchets 17. The pawl heads have their inclined surfaces 27 oppositely arranged to correspond with the opposite arrangement 105 of the ratchet teeth.

The pawls are urged into engagement

with the ratchets by coil springs 30. As it is quite logical that the gears and ratchets will wear in the course of time, it is necessary to have an adjustment to compensate 5 for this condition and I therefore provide the adjustable bracket members 22 above described.

The throw-out mechanism comprises a pair of small levers 31 located on opposite 10 sides of the lever 18 and pivoted thereto by a common bolt or spindle 32. The ends of the spindle are squared so that both levers will move together. On the levers are handles 33 and connected with the levers are 15 wires 34 or other flexible members which extend through guides 35 on the lever 18 and which are connected with eyes 36 on the plungers 25. On the lever 18 are stops 37 engageable by the levers 31 for holding 20 them in the dotted position shown in Figure 2 in which position the pawls are held entirely out of engagement with the ratchets.

The device may be used in a great variety of different ways, and in the position shown 25 in Figure 1. In case it is employed in conjunction with a windmill or the like, it may be mounted on a suitable concrete base 39 and in the position shown in Figure 3 and held by a plurality of inclined braces 40 30 connected with the frame at suitable points. The operating lever 18 is then preferably connected with the windmill pitman by means of a frame 41 on the pitman 42 and within which are journaled rollers 43 35 which surround the lever 18 and which reduce friction. Power may be taken off from the shaft 16 in any desired manner, as for instance, by the gear 44.

To enclose and protect the working parts 40 of the device, I provide a base pan 45 which is secured to the frame 10. Cooperating with this pan is a similar or mating pan member 46 which constitutes a housing or cover and which is formed with an elongated slot 47 along which the lever operates. 45

In the operation it will be seen that when the lever 18 is reciprocated, the pawls 26 50 will co-act with the ratchets 17 for rotating the gears 14 and consequently driving the pinion 15 and shaft 16. When the lever moves in one direction, one pawl will engage one ratchet while the other pawl will have its inclined end ride idly over the other ratchet. On the return stroke of the lever, 55 the pawl action is reversed, but owing to the peculiar arrangement of the gearing, it is apparent that the shaft 16 will still be driven in the same direction. By properly

designating and correlating the parts it is 60 possible to eliminate dead center or lost motion so that a continuous rotary movement will be the output from the device.

In Figure 7 I have shown another form in which the gears 50 corresponding to the gears 14 are equipped on their outer faces 65 with ratchets 51 corresponding to the ratchets 17. Co-acting with these ratchets 51 are spring pressed pawls 52 carried by stems 53 slidable through the operating lever and carrying nuts 54. This form acts in the 70 same way as the first described form but the pawls are releasable by means of cam plates 55 which are slotted at 56 and which are slidable on the frame. The lever in this instance is forked and rotatably mounted 75 outwardly of the gears. In either or both forms I may provide roller bearings 57 for the shaft 13 mounted as shown, and roller bearings 58 for the shaft 16.

While I have shown and described the 80 preferred embodiment of my invention it is, of course, to be understood that I reserve the right to make such changes in the form, construction and arrangement of parts as will not depart from the spirit of the invention or the scope of the subjoined claims.

I claim:

1. In a device of the character described, a frame, a shaft journaled therein, gears rotatable on said shaft, a driven gear between and meshing with both of said gears and mounted on a shaft, an oscillating lever pivoted on said shaft between the first named gears, ratchets carried by said first named gears, pawls on the lever cooperating with said ratchets, and means for adjusting the positions of said pawls to compensate for wear on the gears and ratchets. 90 95

2. In a device of the class described, a frame, a shaft journaled therein, gears rotatable on said shaft, a driven gear between and meshing with both of said gears and mounted on a shaft, an oscillating lever pivoted on said shaft between the first named gears, ratchets carried by said first 100 105 named gears, pawls on the lever cooperating with said ratchets, said pawls being carried by spring pressed plungers, flexible elements connected with the plungers, levers connected with the flexible elements, and means engageable by the levers for holding them in position applying tension to the flexible elements and withdrawing the pawls from engagement with the ratchets. 110

In testimony whereof I affix my signature.
ALBERT H. DRAKE.
